DESIGN FOR A BATHING SUIT

Charna J. L. Anderson, New York, N. Y., assignor
to The Worcester Knitting Company, Worcester,
Mass., a corporation of Massachusetts

Application September 5, 1939, Serial No. 87,051

Term of patent 3½ years

To all whom it may concern:

Be it known that I, Charna J. L. Anderson, a citizen of the United States, residing at New York, in the county of New York and State of New York, have invented a new, original, and ornamental Design for Bathing Suit, of which the following is a specification, reference being had to the accompanying drawing, forming part thereof.

Fig. 1 is a perspective view of a bathing suit showing my new design as it appears when worn;

Fig. 2 is a fragmentary rear view, on a larger scale, of the bathing suit shown in Fig. 1 as it appears when laid out flat; and

Fig. 3 is a fragmentary front view, on a larger scale, of the bathing suit shown in Fig. 1 as it appears when worn.

The back of the bathing suit is conventionally plain except for the ruffle.

The characteristic feature of my design resides in the combination on the bathing suit disclosed of the specific knitted ruffle attached adjacent the bottom, as shown.

I claim:

The ornamental design for a bathing suit, as shown and described.

CHARNA J. L. ANDERSON.
